(57) **CLAIM**

The ornamental design for a truck box rack for cab protection and long cargo, shown and described.

DESCRIPTION

FIG. 1 is a perspective view of the truck box rack and cab protector;

FIG. 2 is a rear elevational view of the front truck box rack and cab protector;

FIG. 3 is a top plan view of the front truck box rack and cab protector;

FIG. 4 is a bottom plan view of the front truck box rack and cab protector; and,

FIG. 5 is a side elevational view of the front truck box rack and cab protector.

The truck rack is shown on an enlarged scale in FIGS. 2-5.

The broken line showing of environment is for illustrative purposes only and forms no part of the claimed design.
